(57) **CLAIM**

The ornamental design for a dual purpose suction head device for squeegee actuated carpet cleaning and for rotatable conversion to brush floor cleaning, as shown and described.

DESCRIPTION

FIG. 1 is a front view of a dual purpose suction head device for squeegee actuated carpet cleaning, and for rotatable conversion to brush floor cleaning;

FIG. 2 is a top view thereof;

FIG. 3 is a rear view thereof;

FIG. 4 is a bottom view thereof;

FIG. 5 is a right side view, the left side view being the mirror image thereof; and,

FIG. 6 is an upper perspective view thereof.
